United States Patent Office

Des. 204,876

Patented May 24, 1966

204,876

ELECTRIC CAN OPENER

Henry J. Talge, Kansas City, Mo., assignor to Dazey Products Company, Kansas City, Mo., a corporation of Missouri

Filed Sept. 15, 1965, Ser. No. 87,015

Term of patent 14 years

(Cl. D22—2)

FIG. 1 is a front elevational view of the electric can opener;

FIG. 2 is an elevational view of one side thereof;

FIG. 3 is an elevational view of the opposite side thereof;

FIG. 4 is a rear elevational view thereof; and

FIG. 5 is a top plan view thereof.

I claim:

The ornamental design for an electric can opener, as shown.
